UNITED STATES PATENT OFFICE.

ANDRÉ HARRIBEY AND EDMOND COMBECAVE, OF BORDEAUX, FRANCE.

HEEL-PROTECTOR FOR BOOTS OR SHOES.

1,366,177.

Specification of Letters Patent. Patented Jan. 18, 1921.

Application filed April 29, 1920. Serial No. 377,647.

To all whom it may concern:

Be it known that we, ANDRÉ HARRIBEY and EDMOND COMBECAVE, citizens of the French Republic, both of 37 Chemin de Pessac, Bordeaux, France, have invented certain new and useful Improvements in Heel-Protectors for Boots or Shoes, of which the following is a specification.

This invention relates to improvements in heel protectors for boots or shoes.

The present invention consists in a new method of preservation of the heels of shoes against rapid wear by means of rubber cubes of prismatic and segmentary shape held in a hinged metal box which is connected to the heel by means of screws.

The device comprises two main elements: 1 a box formed in two parts: 2 rubber heel blocks fixed by said box.

20 The annexed drawings illustrate the invention in which:—

Figure 1 is a perspective view of the metal framework arranged against a boot-heel but not secured by the screws, the rubber blocks 25 being illustrated by dotted lines.

Fig. 2 is a perspective view of the central screw.

Fig. 3 is a diagrammatic perspective view 30 of the two parts of the metal framework and of the hinge serving to connect them.

Fig. 4 is a perspective view of one form of the two rubber heel-blocks.

Fig. 5 is a view in section on line A—B of Fig. 7, showing the complete apparatus fixed 35 in place on the heel of a shoe.

Fig. 6 is a perspective view of a second form of rubber heel block which is of segmentary shape.

Fig. 7 is a plan view of the metal box 40 showing the three apertures in which the rubber heel blocks are inserted and showing the hole through which passes the central screw.

The box has a base *a* fixed on the heel by 45 screws *b* *b*¹ and is provided with a screw eye *c*¹ at the center for the reception of a screw *c*. This base is connected by a hinge *d* *d*¹ to the box lid *e*, the wall of which is oblique and which comprises three apertures provided at their peripheries with claws *g*: a depression *h* serves as socket for the screw-head *i* provided with two projections *i*¹ which fit into two corresponding recesses *i*² in order to produce the locking of the 55 screw *c*.

The detachable rubber heel-blocks *j*¹ *j*² are

formed with shoulder-pieces *k* *k*¹ resting on the inner base of the lid *e*, the projecting parts *j* resting on the ground. These heel-blocks engage in the respective apertures *f* 60 and are held in place by their shoulder-pieces and by the penetration of the claws *g*.

The fixing on the heel *C* of the shoes is done as follows: The bottom of the box is first fastened underneath the heel of the shoe 65 as described, then the rubber heel-blocks are inserted in their apertures, then the box-lid is turned down on the said bottom, the latter is fastened by means of the screw *c*.

The metal parts may be manufactured of 70 various metals, and it can be readily understood that in case of wear, any or all of the rubber heel-blocks can be replaced as required.

It is to be remarked that the extraction of 75 the rubber heel-blocks for the purpose of replacing them when they are worn away, can be very easily effected without the aid of any tool other than a coin inserted in the notch *l* of the screw-head *c* for unscrewing 80 the latter and enabling the metal box *e* to be opened.

What we claim as our invention and desire to secure by Letters Patent of the United States is:—

1. A protector for shoe heels comprising a flat plate adapted to be fixed to the under surface of the shoe heel, a lid hinged to said plate and forming therewith a flat box, said lid having one or more apertures in its flat face, one or more removable flat blocks of rubber within said box and having parts of reduced size extending through said apertures beyond said face to form tread surfaces and means for locking said lid to said 95 plate.

2. A protector for shoe heels comprising a flat plate adapted to be fixed to the under surface of the shoe heel, a lid hinged to said plate and forming therewith a flat box, said lid having one or more apertures in its flat face, claws on the edges of said apertures, one or more flat blocks of rubber extending through said apertures, said blocks having flanges extending over the inner surface of 105 the flat face of said lid around said apertures and having a thickness approximately equal to the exterior depth of the box, and means for locking said lid to said plate.

3. A protector for shoe heels comprising a 110 flat plate adapted to be fixed to the under surface of the shoe heel, a lid hinged to said

plate and forming therewith a flat box, said lid having one or more apertures in its flat face, claws on the edges of said apertures, one or more flat blocks of rubber extending 5 through said apertures, said blocks having flanges extending over the inner surface of the flat face of said lid around said apertures and having a thickness approximately equal to the exterior depth of the box, an 10 internally screw-threaded boss fixed to said plate, a screw passing through said lid and

screwed into said boss to lock said lid and means for locking said screw.

In witness whereof we have signed this specification in the presence of two wit- 15 nesses.

ANDRÉ HARRIBEY.
EDMOND COMBECAVE.
